CLAIM

The ornamental design for an electromagnetic relay, as shown and described.

DESCRIPTION

FIG. 1 is a front view of a design for an electromagnetic relay according to the present disclosure.

FIG. 2 is a rear view of the electromagnetic relay of FIG. 1. FIG. 3 is a left side view of the electromagnetic relay of FIG. 1.

FIG. 4 is a right side view of the electromagnetic relay of FIG. 1.

FIG. 5 is a top plan view of the electromagnetic relay of FIG. 1.

FIG. 6 is a bottom plan view of the electromagnetic relay of FIG. 1; and,

FIG. 7 is a reference perspective view of the electromagnetic relay of FIG. 1.

The Dash-Dash broken line portion of the figure drawings is included to show portions of the article that form no part of the claimed design. The Dash-Dot broken line portion of the
